APPARATUS FOR MAKING RUBBER THREAD

John R. Gammeter, Akron, Ohio, assignor, by
mesne assignments, to United States Rubber
Company, New York, N. Y., a corporation of
New Jersey

Application August 6, 1932, Serial No. 627,744

3 Claims. (Cl. 18—15)

This invention relates to the manufacture of rubber strips and to a method and apparatus for the continuous and rapid production of such strips in a simple and inexpensive manner from a suitable rubber-containing fluid, such as a solution or dispersion of rubber or rubber-like material.

Other advantages will readily appear from the following description, reference being made to the accompanying drawing, in which:

Figure 1 is an elevation more or less diagrammatically illustrating an apparatus and method embodying and carrying out the invention;

Figure 2 is a detail front elevation showing an apparatus for applying the rubber-containing fluid to the travelling belt of Fig. 1; and

Figure 3 is a detail side elevation of a modified apparatus for applying the rubber-containing fluid to the travelling belt of Fig. 1.

Referring to the drawing, the numeral 10 designates a tank for a rubber-containing fluid 11, preferably an aqueous dispersion of rubber, such as natural latex containing vulcanizing ingredients so that on subsequent drying and heating

rubber deposited from it will become vulcanized. In the tank is an apparatus for applying one or more laterally confined films of the rubber-containing fluid to a travelling surface with which the apparatus substantially contacts. The apparatus is in the form of one or more hardened printing rolls 12 or similarly constructed roll, journaled in the tank 10 and partly submerged in the rubber-containing fluid 11. The printing roll, shown in detail in Fig. 2 consists of two wall

surfaces 13 and 14 which hold the rubber-containing fluid between them by virtue of the groove 15, and when the wall surfaces 13 and 14 are at an angle to the belt 18 and substantially touch it at the edges 16 and 17 of the wall surfaces, the fluid is transferred to the surface in the form of a laterally confined film. This is unlike the application of a fluid to an advancing surface by means of an ordinary applicator roll with the applying surface completely in contact with the travelling surface. With the ordinary applicator roll, the fluid is not applied to the advancing surface in the form of a laterally confined and regular film, but is licked off the roll in the form of a film that will have more or less irregular edges and possibly contain fissures. As the printing roll 12 rotates in the tank 10, the walls 13 and 14 are wiped or cleaned by ploughs 19 so that the applied film will present a sharply defined edge and be uniform.

Figure 3 shows another means of applying a

laterally confined film to the advancing surface, wherein the printing roll 12 instead of being journaled in a tank and being partly submerged in the liquid, as in Fig. 1, is fed from a fountain consisting for example of a tank 10' containing rubber-containing fluid 11', by means of a discharge orifice 20 substantially touching the groove 15 of the printing roll 12 so that only on rotation of the roller and application of the rubber-containing fluid in the groove to the advancing surface 18, will the rubber-containing fluid 11' continue to feed to the groove. Other methods of feeding the rubber-containing fluid to the printing roll will readily occur to persons skilled in the art.

The advancing surface 18 to which the rubber-containing fluid is applied takes the form of an endless metallic belt, preferably of stainless steel. The surface of the belt on which the rubber dispersion is deposited should be maintained smooth and clean so that a film of dispersion applied to it from the printing roller will completely hold together and continue to be in the form of a strip as applied with laterally confined edges and on subsequent drying may be removed from the surface without unduly adhering to it in spots and possibly producing fissures in the strip or even completely rupturing it. In order to present such a surface before applying the dispersion thereon, a cleaning apparatus such as a buffer 21 is provided to clean the surface of the belt prior to applying the rubber dispersion to it.

As the rubber-containing fluid is applied to the belt, the belt travels over idler 22 provided with grooves on its surface so that the films of dispersion will not come in contact with it, and the films are dried and vulcanized by passing through chamber 23, through which air or other gas heated to a temperature sufficient to produce drying and vulcanization, is blown by blower 24 associated with gas heating chamber 25, and around take-up pulley 26.

The dried rubber strips are removed from the belt at an angle thereto under tension by a stripping operation at some point of travel of the belt before the buffer 21. The belt is shown going around idler 27 and driving pulley 28 (driven by means not shown) and the strips are removed from the pulley 28 at take-off point 29 by take-off rolls 30 and 31 and wound up on one or more spools 32.

In operation the strip or strips of rubber are continuously removed from the belt 18 at take-off point 29 and the belt buffed by buffering apparatus 21 and the process continued, the laterally con-

fined films of rubber dispersion being applied to the buffed surface of the belt, the belt advancing through the drier and vulcanizer 23 so that the applied films will be dried and vulcanized, and 5 the vulcanized strips are removed at take-off point 29 by means of take-off rolls 30 and 31.

The rubber-containing fluid applied to the continuously progressing surface, as has been stated, is preferably an aqueous dispersion of rubber, 10 such as natural latex containing vulcanizing ingredients so that on passing through the heating chamber, vulcanized strips will be formed. The rubber-containing fluid may be a vulcanized latex or the like so that a subsequent vulcanization on 15 drying is unnecessary. If desired, an unvulcanized latex may be used that contains no vulcanizing ingredients, or one may be used that contains vulcanizing ingredients but that will not produce vulcanization under the conditions in 20 chamber 23. In such case the belt after leaving the drying chamber 23 may pass through a separate vulcanizing chamber and before removing from the belt. Also, if desired, in such case, the strips may be vulcanized after being removed 25 from the belt and before spooling, or while on the spools, or during some subsequent operation after unwinding from the spools. The use of other well known aqueous dispersions of rubber or rubber-like material, including artificial dispersions of crude and reclaimed rubber, or rubber-

like material, will be apparent to persons skilled in the art.

As various other modifications will occur to those skilled in the art, it is not intended to limit the invention other than as set forth in the appended claims. 5

Having thus described my invention, what I claim and desire to protect by Letters Patent is:

1. An apparatus for making strip rubber comprising a travelling liquid impervious surface, a 10 grooved roller for applying a film of rubber-containing fluid thereon, means for drying the rubber film, means for removing the dried film in strip form from the surface, and means for cleaning the bare surface as it advances. 15

2. An apparatus for making rubber comprising an endless liquid impervious belt, a grooved roller for applying a film of rubber-containing fluid thereon, means for drying the rubber film, means 20 for removing the film in strip form from the belt at an angle thereto under tension, and means for buffing the belt after removal of the film. 20

3. An apparatus for making strip rubber comprising a travelling liquid impervious surface, a 25 grooved roller for applying a laterally confined film of rubber-containing fluid thereon, means for heating the rubber film on the surface, and means for removing the film from the surface. 25

JOHN R. GAMMETER.
